EXHAUSTER FOR SPRINKLER SYSTEMS

Filed July 27, 1928

FIG. 1.

FIG. 2.

Inventor,

William B. Griffith
By F. DeWitt Goodwin
Attorney

UNITED STATES PATENT OFFICE

WILLIAM B. GRIFFITH, OF AUDUBON, NEW JERSEY, ASSIGNOR TO STAR SPRINKLER CORPORATION, A CORPORATION OF NEW JERSEY

EXHAUSTER FOR SPRINKLER SYSTEMS

Application filed July 27, 1928. Serial No. 295,719.

My invention relates to an exhauster for a sprinkler system and particularly relates to an exhauster for use in connection with dry pipe valves now in general use in automatic 5 sprinkler systems for fire protection. My invention particularly relates to an exhauster comprising a casing, having a normally closed exhaust valve with means for opening the same upon a sudden reduction of air 10 pressure in the system with which the exhauster is operatively connected. The object of my invention is to provide an exhauster comprising a casing having the exhaust valve and operating means in one portion 15 thereof and said casing having a separate compartment forming a float chamber which is normally dry when the sprinkler system is closed; a further object is to provide the casing and connections with large 20 passageways permitting the air pressure to exhaust freely and rapidly through the exhauster from the system to the large exhaust valve and exhaust outlet when the system is opened; a further object is to provide a float 25 and a float valve within the float chamber for closing communication through the float chamber to the exhaust valve, subsequently to the opening of the latter, when water is admitted to the float chamber upon the opening 30 of the dry pipe valve of the system, thus preventing the passage of water through the exhauster after the dry pipe valve has opened. These together with various novel features 35 of construction and operation of the parts, which will be more fully hereinafter described and claimed, constitute my invention.

Referring to the accompanying drawing Fig. 1 is a vertical central sectional view of my improved exhauster, and Fig. 2 is a view 40 similar to Fig. 1 showing the parts in a different position.

In the drawings in which like reference characters refer to like parts, 1 represents the casing of the exhauster provided with a connection 2 for the pipe 3 which is in communication with the sprinkler system at a point 45 above the dry pipe valve (not shown in the drawing), whereby the air pressure from the system is admitted through the relatively 50 large pipe 3 to the exhauster.

The casing 1 is provided with a vertical wall 5, which forms a float chamber 6 located within the casing 1 adjacent to the portion of the casing which is provided with said connection 2, whereby air or water entering 55 through the pipe 3 will be received in the float chamber 6. Within the casing 1 and located upon the opposite side of the wall 5 from the float chamber 6, are formed a pressure chamber 10, a neutral chamber 15, and a 60 pressure retaining chamber 20. The pressure chamber 10 is in communication with the float chamber 6 through a large opening 22 formed in the upper portion of the wall 5. A valve seat 23 is located upon the wall 5 65 and surrounds said opening 22.

The casing 1 is provided with a web 25 which is formed integral with the casing and with the wall 5. Said web 25 is provided with a large opening 26, surrounded by a 70 valve seat member 27 having a valve seat 28 and upon which latter the flexible valve ring 30 of the exhaust valve 32 is adapted to seat. The exhaust valve 32 is movable vertically and guided by ribs 33 which slide loosely 75 within the circular wall of the valve seat member 27. Said valve 32 is adapted to control communication between the pressure chamber 10 and the neutral chamber 15, which latter is provided with a large exhaust 80 outlet 16.

The exhaust valve 32 is operated by a flexible diaphragm 35, having attached to the central portion thereof a rod 37, which is pivotally associated with the exhaust valve 85 32. The periphery of the diaphragm 35 is tightly clamped upon a flange 40 formed upon the casing 1 and upon the wall 5 of the casing, by a clamp ring 41, thereby tightly sealing the opening 43 formed through the 90 flange 40. The pressure retaining chamber 20 is thus formed below the diaphragm 35 and the flange 40, which parts separate the chamber 20 from the neutral chamber 15, and the flexible diaphragm 35 causes the exhaust 95 valve 32 to open, or lift off the seat 28, when the air pressure in the retaining chamber 20 is greater than the air in the pressure chamber 10, above the exhaust valve 32.

A cover plate 45 is secured to a vertical 100

facing surface 46, formed upon the casing 1, by means of bolts 47. Said cover plate 45 is provided with a large cavity forming said exhaust outlet 16, which latter is in communication with the neutral chamber 15 formed between the exhaust valve 32 and the diaphragm 35.

The cover plate 45 is provided with a cored passageway 50 which forms a communication between the pressure chamber 10 and the pressure retaining chamber 20.

A slow leak device 51, in the form of a fitting provided with a minute aperture 52, is located within the pressure chamber 10 and secured upon the cover plate 45 at the entrance to said passageway 50. Said device 51 forms a restricted orifice 52 through which the air pressure may slowly pass between the chambers 10 and 20 and thus equalize.

A float valve 55 is located in the float chamber 6 and is adapted to close upon the valve seat 23. The valve 55 is pivoted upon a shaft 56 mounted in a bearing 57 upon the wall 5. An arm 58 upon the valve 55 is loosely pivoted to a supporting rod 60 secured to a float 61 and adapted to support the valve 55 in the open position, shown in Fig. 1, when the float chamber 6 is dry. When the chamber 6 is filled with water the float 61 will lift and close the float valve 55 upon its seat 23, thus preventing water from passing into the pressure chamber 10.

The operation of my invention is as follows; when the sprinkler system is charged, the air pressure from the system will be admitted to the exhauster casing 1, through the pipe 3 and enter the pressure chamber 10 through the opening 22, formed in the wall 5 at the top of the float chamber 6. The pressure in chamber 10 will hold the valve 32 closed, as shown in Fig. 1, and the air pressure will pass through the restricted orifice 52 and the passageway 50 into the pressure retaining chamber 20, thus allowing the pressure to slowly equalize in chambers 10 and 20. The float chamber 6 is normally dry so that the float 61 will remain at the bottom of the chamber 6 and hold the float valve 55 in the open position, shown in Fig. 1.

When the air pressure in the system is reduced by the opening of a sprinkler head, the restricted orifice 52 will retain the pressure in the pressure retaining chamber 20 sufficiently to allow the diaphragm 35 to move outwardly, relatively to the chamber 20, thus lifting the valve 32 against the reduced pressure in the chamber 10, thereby allowing the air pressure from the system to exhaust around the valve 32 and pass to the atmosphere through the exhaust outlet 16.

My novel form of exhauster allows the dry pipe valve to open at an earlier period of time due to the rapid exhausting of the air pressure through the large exhaust outlet 16.

When the dry pipe valve has opened and

water is admitted to the system above the dry pipe valve the water will flow through the pipe 3 into the float chamber 6, causing the float to rise and close the float valve against the valve seat 23, thus closing communication between the system and the pressure chamber 10 and preventing the flow of water through the exhauster. Should the water flowing through the pipe 3 pass through the float chamber and into the pressure chamber 10 before the float valve is closed, the water pressure above the valve 32 will close the latter, providing the water pressure in the chamber 10 is greater than the air pressure in the chamber 20, and as soon as the float chamber 6 receives sufficient water to cause the float to rise and close the float valve, the exhauster will be sealed by the said float valve and prevent the escape of water through the exhauster casing 1. This feature is an advantage in case the air pressure in the retaining chamber 20 is greater than the water pressure in the chamber 10 which would prevent the valve 32 from closing immediately.

My novel form of exhauster permits the use of extremely large exhaust outlet passageways, such as the pipe 3 the opening 22 in the wall 5, the exhaust outlet 16 and the large exhaust valve 32, thus providing means for quickly exhausting the air pressure from the system when the sprinkler head is opened, thereby insuring the quick action of the dry pipe valve and for immediately closing the exhaust outlet of the exhauster when water is admitted to the system through the dry pipe valve.

Various changes of construction, other than those shown in the drawing, may be made without departing from my invention.

I claim:

1. An exhauster for a sprinkler system comprising, a casing having a float chamber formed therein, a connection upon the casing forming a means of communication between the system and said float chamber, said casing having an outlet passageway formed in the upper portion of the float chamber, a valve for closing said outlet passageway, a float within said chamber operatively associated with said valve for closing said passageway when water enters the float chamber, said casing having a pressure chamber formed therein communicating with the float chamber through said outlet passageway from the float chamber, an exhaust valve located in said pressure chamber, normally held closed by the pressure in said chamber, said casing having an exhaust outlet formed therein controlled by said exhaust valve, said casing having a pressure retaining chamber formed therein, a member associated with said retaining chamber movable by relative changes of pressure within said retaining and pressure chambers, said member operably associated with said exhaust valve for opening the

latter, and said casing having a restricted passageway forming a communication between said pressure and retaining chambers.

2. An exhauster for a sprinkler system having a dry pipe valve, comprising a casing forming a float chamber, said casing having a relatively large inlet connection forming a communication between the system above the dry pipe valve and the float chamber, 5 said casing having an outlet passageway formed in the upper portion of the float chamber, a valve operatively mounted upon the casing for closing said outlet passageway, a float operatively associated with the 10 valve for closing said outlet passageway when water enters the float chamber, said casing having a pressure chamber formed therein in communication with the float chamber through said outlet passageway, 15 said casing having an exhaust outlet forming a communication between the pressure chamber and the atmosphere, an exhaust valve for controlling the exhausting of air pressure from the float chamber through said exhaust 20 outlet normally held closed by the pressure in said pressure chamber, and a movable member associated with the exhaust valve actuated by a sudden reduction of pressure in the 25 sprinkler system for opening the exhaust valve.

3. An exhauster for a sprinkler system having a dry pipe valve comprising a casing, 30 said casing having a connection forming a communication between said casing and the system above the dry pipe valve, a wall within the casing forming a float chamber with which said connection is in communication, said wall having a valve seat surrounding an opening located at the upper 35 portion of the float chamber, a valve operatively mounted adjacent to said valve seat, a float within said float chamber operatively associated with said valve for closing the latter when water enters the float chamber 40 through said connection with the system, said casing having an exhaust outlet to the atmosphere, an exhaust valve located between the 45 float chamber and the exhaust outlet for closing the latter, said exhaust valve normally held closed by the pressure in said pressure chamber, and means for opening the exhaust valve upon a sudden reduction of pressure in the system.

4. An exhauster comprising a casing having a float chamber formed therein, a connection upon the casing forming an inlet connection to the float chamber, said casing having a pressure chamber formed therein, a wall within the casing having a passageway 55 formed through the upper portion thereof, a valve for closing said passageway, a float operatively associated with the valve for operating the latter to close said passageway when water enters the float chamber, said 60 casing having a pressure retaining chamber 65

formed therein located in spaced relation to the pressure chamber, said casing having a neutral chamber located between said pressure chamber and said retaining chamber, an exhaust valve for closing a passageway 70 formed between said pressure chamber and said neutral chamber normally held closed by the pressure in said pressure chamber, a movable member operatively associated with the exhaust valve for opening the latter when 75 actuated by a greater pressure within the retaining chamber relatively to the pressure in said pressure chamber, a cover plate detachably secured to said casing, said cover plate having an exhaust outlet formed there- 80 through registering with said neutral chamber, said cover plate having a passageway formed therein forming a communication between said pressure chamber and said retaining chamber, and a slow leak device located 85 in said last mentioned passageway.

5. An exhauster for a sprinkler system comprising, a casing having a pressure chamber formed therein, said casing having a connection forming a communication between the pressure chamber and said system, said casing having a passageway forming an exhaust outlet from the pressure chamber to the atmosphere, an exhaust valve for closing said 90 passageway normally held closed by the pressure in said pressure chamber, said casing having a pressure retaining chamber formed therein, a movable member operatively associated with said retaining chamber, a rod operatively positioned between 95 said movable member and said exhaust valve for opening the latter upon the rapid decrease in pressure in said pressure chamber, said pressure and retaining chambers being located in spaced relation to each other having said exhaust outlet positioned between the exhaust valve and said movable member, said casing having a passageway formed therein 100 communicating between the pressure chamber and the retaining chamber, and a slow leak device located in said last mentioned passageway.

In testimony whereof I affix my signature.

WILLIAM B. GRIFFITH.
